[57] CLAIM

The ornamental design for a frame supported swing, as shown and described.

DESCRIPTION

FIG. 1 is a front perspective view of a frame supported swing, showing my new design.

FIG. 2 is a top plan view thereof.

FIG. 3 is a front elevational view thereof.

FIG. 4 is a right side view thereof, the left side view thereof being identical;

FIG. 5 is a rear elevational view thereof; and,

FIG. 6 is a bottom plan view thereof.

The broken lines shown in all views are for environmental purposes only and form no part of the claimed design.
